UNITED STATES PATENT OFFICE

BENJAMIN PUTTERMAN, OF BROOKLYN, NEW YORK, ASSIGNOR TO YANKEE METAL PRODUCTS CORP., A CORPORATION OF NEW YORK

DESIGN FOR A RADIATOR GUARD

Application filed April 20, 1931. Serial No. 39,574. Term of patent 7 years.

To all whom it may concern:

Be it known that I, BENJAMIN PUTTERMAN, a citizen of the United States, residing in the borough of Brooklyn, county of Kings, city and State of New York, have invented a new, original, and ornamental Design for Radiator Guard, of which the following is a specification, reference being had to the accompanying drawings, forming a part thereof.

Fig. 1 is a front view of a radiator guard illustrating my new design;

Fig. 2 is a top plan view thereof.

I claim:

The ornamental design for a radiator guard, substantially as shown.

This specification signed this 18th day of April, 1931.

BENJAMIN PUTTERMAN.
